Primary Examiner—Jeffrey Asch*Assistant Examiner*—Bridget L. Eland(74) *Attorney, Agent, or Firm*—Birch, Stewart, Kolasch & Birch, LLP(57) **CLAIM**

The ornamental design for a mobile phone, as shown and described.

DESCRIPTION

FIG. 1 is a perspective view of a mobile phone showing my (our) new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a front view thereof in a condition that the lower body thereof has been slid downward and the inner key pad is exposed.

The broken line showing in FIG. 7 of interior features, including the keypad, is for illustrative purposes only. and forms no part of the claimed design.
